UNITED STATES PATENT OFFICE.

CHARLES W. BECK, OF NEW YORK, N. Y., ASSIGNOR TO ELECTRO LAMP COMPANY, OF NEW YORK, N. Y., A CORPORATION OF WEST VIRGINIA.

DESIGN FOR A LAMP.

SPECIFICATION forming part of Design No. 35,508, dated December 31, 1901.

Application filed November 7, 1901. Serial No. 81,485. Term of patent 14 years.

To all whom it may concern:

Be it known that I, CHARLES W. BECK, a citizen of the United States, residing at New York city, in the borough of Manhattan and State of New York, have invented and produced a new and useful Design for a Lamp, of which the following is a full, clear, and exact specification, reference being had to the accompanying drawing, wherein the single figure of the drawing represents in side elevation an embodiment of my design.

A lamp embodying my design is characterized by consisting of three salient or main features—namely, a lower base portion, (designated as 1,) an upper bowl or main body portion, (designated 2,) and an intermediate contracted connecting waist portion 3. The base portion has a rounded convex top portion 6

and a flat bottom 4. The intermediate waist portion 3 constitutes a pillar mounted concentrically and vertically upon the base member 1 and having circular side walls 7 extending throughout its principal height, but terminating at its lower or base end in a cylindric portion 8.

The main body or bowl of the lamp 2 comprises a lower convex and upwardly-flaring or bowl-shaped portion 9 and a top portion 10.

I claim as new—

The design for a lamp as herein shown and described.

CHARLES W. BECK. [L. S.]
